UNITED STATES PATENT OFFICE.

JOHN RUSH GREEN, OF SOMERVILLE, FRANKLIN S. WILLIAMS, OF WINTHROP, AND JOSEPH AIMÉ LAVALLÉE, OF DORCHESTER, MASSACHUSETTS, ASSIGNEES TO JOHN RUSH GREEN, OF CHARLESTOWN, MASSACHUSETTS.

SHOE RACK.

Application filed April 9, 1921. Serial No. 450,918.

To all whom it may concern:

Be it known that we, JOHN RUSH GREEN and FRANKLIN S. WILLIAMS, both citizens of the United States, and JOSEPH AIMÉ LAVALLÉE, a subject of the King of Great Britain, residents of Somerville, county of Middlesex, of Winthrop, county of Suffolk, and of Dorchester, county of Suffolk, State of Massachusetts, respectively, have invented 10 an Improvement in Shoe Racks, of which the following description, in connection with the accompanying drawing, is a specification, like characters on the drawing representing like parts.

15 This invention relates to improvements in racks for holding boots or shoes which are commonly used in factories to support the boots or shoes while undergoing various processes of manufacture and to transport 20 the shoes from one part of the factory to another.

The more desirable forms of shoe racks comprise end frames which are connected by transverse bars which carry a plurality of 25 shoe supports having free ends recessed or otherwise spaced apart to receive the uppers therebetween when the shoes are inverted so that the soles are upward, the shoe supports desirably being provided with separators 30 to retain the shoes in place when in upright positions with the soles resting upon the shoe supports.

More specifically the invention relates to 35 improvements in shoe racks of the type illustrated in Patent No. 1,058,194, granted April 8, 1913, to Edward F. O'Brien, assignor to John Rush Green. In this construction the shoe supports are secured at their rear ends only, the transverse bars being connected to the end frames. It has been difficult in such constructions to secure the 40 ends of the shoe supports rigidly to said transverse bars and in use the supports frequently become loosened or detached. One 45 of the principal objects of the present invention is to provide means for more rigidly supporting the shoe supports and also for anchoring the same rigidly in position in such a manner that they cannot become 50 loosened or detached.

By reason of the fact that the majority of the transverse parts, which connect the end frames in such constructions, are at one side, the rough handling by the operators

who grasp the upright end frames to push or 55 pull the rack around causes the connections between the transverse members and the end frames to loosen so that the rack soon becomes rickety. Another object of the invention is to provide a shoe rack of this type 60 which will be of a more rigid construction than heretofore produced.

A further object of the invention is to provide an improved means for supporting the shoe supports in such a manner that their 65 free ends will extend upwardly from the horizontal thereby preventing the shoes from falling off of the rack as it is moved from place to place.

Where shoes are held in such racks in inverted position it is desirable that the toe 70 shall be supported upon some smooth and soft surface so that the finish will not be damaged. The present invention contemplates the provision of a transverse supporting bar upon which the toes of the shoe may rest, this bar desirably being so constructed that it may be removed and replaced or recovered.

A further object of the invention is to provide a single transverse toe supporting bar 75 of the character described which not only may be removed, but which may be reversed so that as one portion of the covering of the bar becomes worn it may be rotated about its 80 axis sufficiently to present a fresh surface to be engaged by the toes of the shoes.

Other objects and features of the invention will more fully appear from the following description and the annexed drawings 85 and will be particularly pointed out in the accompanying claims.

In the drawings:

Fig. 1 is a front elevation of a rack for 90 boots or shoes embodying our invention;

Fig. 2 is a detail transverse sectional view 95 showing one of the shoe supporting sections of the rack; and,

Fig. 3 is a plan view of the rack, certain 100 portions of the frame being shown in section to illustrate the manner by which the transverse members are connected to the end frames.

The rack comprising a preferred embodiment of the invention which is illustrated 105 in the accompanying drawings comprises a base 1 desirably supported upon castors 2 and having upwardly extending end frames.

3, 4, which desirably are skeletonized and consist of upright corner posts 5 connected by horizontal beams 6. The rear posts of the frame are connected by a series of rear 5 transverse members 7 which preferably are provided at their ends with tenons 8 set in mortises in the posts 5 and secured therein by spikes or screws 9. The forward under faces of the transverse rear members are 10 provided with recesses 10 to receive the ends of shoe supporting members 11.

The end frames are also connected by a vertical series of intermediate transverse members 12 which desirably are provided 15 with squared end portions 13 set in recesses 14 in the horizontal beams 6 of the end frame. These intermediate transverse members desirably are also provided with tenons 15 which extend through mortises in 20 said beams and are retained therein by spikes or screws 16. Thus it will be observed that the end frames are connected rigidly by transverse members which are spaced apart and tenoned into the end posts 25 and beams connecting the end posts respectively. By reason of this construction a very rigid frame is provided.

The intermediate transverse member desirably is in a different and lower plane 30 than the rear transverse member and the walls of the mortises 14 desirably are inclined to the vertical so that the upper surface 17 of the intermediate transverse member is inclined to the horizontal.

35 The shoe supporting members, which are effectively in pairs, rest intermediate of their ends upon the upper surface 17 of the intermediate transverse member and desirably are secured by fasteners 18. One end 40 of each member of the series of shoe supporting members extends into the recess 10 in the under face of the rear transverse supporting member 7 and is anchored thereto by fasteners 19. The free ends 20 of the 45 shoe supporting members extend upwardly from the horizontal so that the shoes are prevented from falling from the supports while the rack is being transported.

The front ends of the shoe supporting 50 members are spaced apart or provided with recesses 21 to receive the uppers of the boots or shoes when the latter are in inverted position with their soles upward. Under certain conditions, however, the shoes are 55 placed with the soles downward upon the support end to prevent the shoes from striking against each other each of the shoe supporting members is provided with a longitudinal separating member 22 which extends 60 upwardly a considerable distance above the upper surface of the shoe supporting member.

In order properly to support the shoe in inverted position it is desirable that the 65 toe shall rest upon a relatively soft surface

which will not damage its finish. Where cloth covered surfaces have been used for this purpose the covering has worn away so that it is necessary to replace the same and heretofore it has been difficult to renew the 70 surface of the toe support. In the present construction the separators 22 are provided with a series of aligned apertures or recesses 23 which preferably extend upwardly from the under surface of the separator and desirably are in substantially semi-circular 75 form. A reversible toe support extending entirely across the plane is inserted through these apertures and desirably is so secured at its ends that it can be readily detached, 80 reversed, or if desirable removed from the frame.

In the preferred embodiment of the invention illustrated the toe support consists of a cylindrical bar 24 which is provided 85 with a covering 25 of cloth or other soft material, the ends of the bar 24 being secured by screws 26, or other detachable fastenings, to the end frames. It will be obvious that the cylindrical bar can be readily 90 reversed by merely withdrawing the screws, rotating the bar a one-half revolution and re-inserting the screws, or by providing a plurality of screw holes upon different diameters the bar can be readily 95 adjusted to various positions so that new surfaces will be presented for the toes of the shoe to rest upon. When the covering of the bar is worn out the bar can be readily replaced by merely removing the fastenings and withdrawing the bar lengthwise through the apertures 23. It may then be recovered and re-introduced into its place.

It will be understood that the embodiment 100 of the invention disclosed herein is of an 105 illustrative character and is not restrictive and that various modifications in form, construction and arrangement of parts may be made within the spirit and scope of the following claims.

Having thus described our invention, what we claim as new, and desire to secure by Letters Patent, is:

1. A rack for boots or shoes comprising 110 end frames, transverse intermediate and rear members connecting said end frames, supporting members for the boots or shoes resting intermediate of their ends upon the upper surface of said intermediate transverse member and having one end extending beneath and rigidly anchored to the rear transverse member, the other end of said members projecting beyond said intermediate member, the projecting ends of said members being spaced apart to provide 115 apertures to receive the uppers of the shoes.

2. A rack for boots or shoes comprising 120 end frames, an intermediate and a rear transverse member connecting said end frames and located in different planes, the 125

- intermediate member being provided with an upper face inclined to the horizontal, supporting members for the boots or shoes resting upon the inclined face of said intermediate transverse member and having one end projecting therebeyond and the other end extending beneath the rear transverse member, whereby the free end of the shoe supporting members will be inclined upwardly from the horizontal and means for rigidly securing said shoe supporting members to said transverse members.
3. A rack for boots or shoes comprising end frames, a transverse rear member connecting said end frames, an intermediate transverse member of rectangular cross section having its ends seated in mortises in the end frames provided with walls inclined to the vertical, whereby the upper face of said member is inclined to the horizontal, a plurality of shoe supporting members resting upon the upper face of said intermediate transverse supporting member and underlying at one end said rear transverse supporting member, whereby the free ends of said shoe supporting members will be inclined upwardly from the horizontal, said free ends being separated to provide spaces for the uppers of the shoes.
4. A rack for boots or shoes comprising end frames and transverse connecting members, a plurality of pairs of boot or shoe supporting members, said pairs of supporting members being so constructed as to receive between them and to hold boots or shoes with the sole upward and separated from other boots or shoes, longitudinal separators extending upwardly from said shoe supporting members provided with aligned apertures located below the upper edges of said separators and a reversible transverse toe supporting bar covered with soft non-abrasive material extending through said apertures and removably connected at its ends to said end frames whereby said toe supporting bar may be removed and reversed or replaced when the covering becomes worn.
5. A rack for boots or shoes comprising end frames, a plurality of rear transverse members connecting said end frames, a plurality of intermediate transverse members connecting said frames and lying in a different horizontal plane from said rear transverse members, a plurality of pairs of shoe supporting members resting upon said intermediate transverse members and at one end extending beneath the rear transverse members, recesses intermediate of the free ends of said supporting members to receive the shoe uppers, longitudinally extending separators projecting upwardly from said shoe supporting members and having aligned apertures located above said intermediate transverse member, a cylindrical toe supporting member having a soft cover extending through said apertures and means for removably securing the ends of said toe supporting member to said end frames.

In testimony whereof, we have signed our names to this specification.

JOHN RUSH GREEN.

FRANKLIN S. WILLIAMS.

JOSEPH AIME LAVALLÉE.
